CLAIM

The ornamental design for an all-in-one video conference machine, as shown and described.

DESCRIPTION

FIG. 1 is a top, front and right side perspective view of an all-in-one video conference machine showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a top, front and right side perspective view thereof, shown in an alternate configuration.

The broken lines in the drawings depict portions of the all-in-one video conference machine that form no part of the claimed design.

The oblique shade lines in the drawings show transparency.
